US00D779151S

(12) **United States Design Patent** (10) **Patent No.:** **US D779,151 S**
Clements et al. (45) **Date of Patent:** **** Feb. 21, 2017**

(54) **SHAPED TORTILLA**

(71) Applicant: **General Mills, Inc.**, Minneapolis, MN (US)

(72) Inventors: **Robert G Clements**, Plymouth, MN (US); **Shivakumar Elayedath**, Eden Prairie, MN (US); **Amy R. Fleury**, Arden Hills, MN (US); **Zachary Harder**, Crystal, MN (US)

(73) Assignee: **General Mills, Inc.**, Minneapolis, MN (US)

(**) Term: **14 Years**

(21) Appl. No.: **29/476,443**

(22) Filed: **Dec. 13, 2013**

(51) LOC (10) Cl. **01-01**

(52) U.S. Cl.

USPC **D1/122; D1/125**

(58) **Field of Classification Search**

USPC D1/100–130, 199; D7/504, 509, 510, D7/523, 524, 555, 566, 568, 584–587, D7/602, 672, 300.1, 629, 653, 654, 667, D7/400; D21/386; D19/91; 426/92, 94, 426/95, 99, 101, 138–139, 143, 279, 282, 426/283, 391, 514; D11/146, 151, 154; D14/480.5, 484.1

(57) **CLAIM**

The ornamental design for a shaped tortilla, as shown and described.

DESCRIPTION

FIG. 1 is a top perspective view of the shaped tortilla; FIG. 2 is a bottom perspective view of the shaped tortilla of FIG. 1; FIG. 3 is an end view of the shaped tortilla of FIG. 1; FIG. 4 is a side view of the shaped tortilla of FIG. 1; FIG. 5 is a cross-sectional view of the shaped tortilla of FIG. 1, taken along line 5-5 in FIG. 3; FIG. 6 is a top view of the shaped tortilla of FIG. 1; and, FIG. 7 is a bottom view of the shaped tortilla of FIG. 1. The evenly-spaced broken lines in FIGS. 1-7 illustrate portions of the shaped tortilla that form no part of the claimed design. The dash-dot-dash broken lines in FIGS. 1-7 illustrate the boundary of the claimed design which forms no part thereof.

1 Claim, 3 Drawing Sheets
